LIQUID DISPENSER

Richard W. Beall, Jr., Hermosa Beach, Calif., assignor of one-half to Linden H. Chandler, Lomita, Calif.

Application May 19, 1958, Serial No. 50,945

Term of patent 14 years

(Cl. D62—2)

Figure 2 is a side elevational view of the dispenser; Figure 3 is a bottom plan view of the dispenser; and Figure 4 is a top plan view thereof.

I claim:

The ornamental design for a liquid dispenser, as shown.
